UNITED STATES PATENT OFFICE.

GEORGE E. WILBUR, OF TAUNTON, MASSACHUSETTS, ASSIGNOR TO THE WEIR STOVE COMPANY, OF SAME PLACE.

DESIGN FOR A HEATING-STOVE.

SPECIFICATION forming part of Design No. 20,785, dated May 26, 1891.

Application filed March 9, 1891. Serial No. 384,391. Term of patent 7 years.

To all whom it may concern:

Be it known that I, GEORGE E. WILBUR, of Taunton, in the county of Bristol and State of Massachusetts, a citizen of the United States, have invented a new and original Design for Heating-Stoves, of which the following is a full, clear, and exact description, reference being had to the accompanying drawing, forming a part of this specification, in explaining its nature.

The design relates to a heating-stove, and especially to the design for the front, the end, the top, and the foot rail.

The design for the front may be said to be in two parts—namely, that which relates to the door and that which surrounds the door. The door is a fanciful sketch representing, it may be said, one of the seasons, and consists of three merry urchins dancing along with a dog at one side and a border of vine and clusters of grapes. Above this door-plate is a name-plate having a straight lower edge, a curved upper edge, and a surface made up of rounded projections with three conventional flowers thereon.

Upon each side of the door-plate and name-plate is a design consisting of a conventional vine and leaves extending from the lower edge upward in a serpentine course, with radiating leaves in the form of scrolls from each curved section, the upper end of the design having a leaf, which extends horizontally. The end plate comprises an oval center somewhat rounded and in the form of a medallion with a border of small knobs. From this radiate the wavy ribs, which extend to a border made up of lines the sides and bottom of which are straight and the top of which is curved. Lapping upon each of the upper corners is a figure in the nature of a rosette, and it consists of a central point and peculiarly-curved bars extending from said point to fill the corners of the plate. Below the horizontal border-lines is a conventional vine-and-leaf figure, which is mounted over a base of ribs extending upward and narrowing from their upper edges downward.

The design for the top plate comprises a circular ring or border at the center of the plate, leaves extending to each corner of the plate—four in number—a scroll-work of an

ornamental character between the leaves, and ribs upon the end sections extending from the scroll-work to the edge of the plate.

The design for the foot-rail comprises a straight section smooth and curved and two curved arms, which extend inward and upward and at their ends are ornamented with rosettes. The corners are ornamented with scroll-work, and there is a leaf-and-line work design between the scrolls and the rosettes. The legs have a conventional leaf design, the broad part of which is uppermost and is provided with two wings extending toward each corner of the leg, and the foot of the leg has upon each side a scroll.

Having thus fully described my invention, I claim and desire to secure by Letters Patent of the United States—

1. In the design for a heating-stove as herein shown and described, the stove door or plate having the figures of the urchins, dog, and border of fruit and vine, as shown and specified.

2. In the design for a heating-stove as herein shown and described, the stove-plate having the conventional figure of a vine and leaves arranged in a serpentine form and having the curved offshoots and heavy leaf effects, as shown and specified.

3. In the design for a heating-stove as herein shown and described, a plate having a rounded or curved upper edge, a straight lower edge, and a surface composed of conventional flowers and small knobs or projections, as shown and specified.

4. In the design for a heating-stove as herein shown and described, the stove plate or door having an oval center-piece, wavy radiating ribs or bars increasing in width from the center, a line-work border, upper corner rosettes, conventional vine-and-leaf work below the lower line-work, as shown and specified.

5. In the design for a heating-stove as herein shown and described, the plate or top having the central circular border of conventional radiating leaves of a large and heavy mold extending to the corner of the plate, scroll-work suggestive of vines and leaves, but regularly formed between the large radiating leaves, and line or rib work upon each

end section of the plate, as shown and specified.

6. In the design for a heating-stove as herein shown and described, a stove-rail having a plain rounded straight section ending in two inwardly-curved and twisted arms, a rosette at the end of each arm, a scroll at each end of the straight section and connecting line-and-leaf work upon the arms, as shown and specified.

7. In the design for a heating-stove as herein shown and described, the stove-foot, upon which is a representation of a large leaf with horizontally-extending sections and rosettes upon each face of the lower end of the foot, as shown and specified.

GEO. E. WILBUR.

In presence of—

GEO. W. BARROWS,
S. M. FRENCH.
